RESISTOR ASSEMBLY FOR CIRCUIT
INTERRUPTERS

Benjamin P. Baker, Turtle Creek, and Erling Frisch, Pittsburgh, Pa., assignors to Westinghouse Electric Corporation, East Pittsburgh, Pa., a corporation of Pennsylvania

Application March 4, 1950, Serial No. 147,734

9 Claims. (Cl. 201—69)

1

This invention relates to resistor assemblies, in general, and more particularly to an improved resistor assembly for use in a circuit interrupter.

A general object of our invention is to provide an improved resistor assembly which will resist shock and which will be particularly suitable for use in a circuit interrupter, particularly a circuit interrupter of the high voltage type.

A more specific object of our invention is to provide an improved resistor assembly in which novel spring means are employed to maintain the cast grid elements in proper position, yet permitting some expansion and contraction due not only to thermal stresses, but also due to the large repulsive magnetic forces involved by virtue of the fact that large amperage currents may pass through the resistor assembly.

A further object of our invention is to provide an improved resistor assembly which will involve a minimum of space and which will not only be compact, but may be easily assembled by unskilled workmen.

Still a further object is to provide an improved resistor assembly particularly adapted for high voltage applications, and in which special provision is made for the prevention of flashover, or progressive creepage breakdown between the resistor grid elements.

Still a further object is to provide an improved resistor assembly in which novel means are utilized for insuring good electrical contact between immediately adjacent resistor elements so that contact heating may be prevented, or at least greatly minimized.

Yet another object of our invention is to provide an improved resistor assembly utilizing novel spring means for maintaining the resistor elements in good contacting engagement, and also to provide means for easily adjusting the spring pressure, not only when the assembly is initially used in an installation, but also during the life of the assembly so that maintenance operations may be easily and quickly made.

A further object is to provide an improved resistor assembly in which an insulating spacer plate separates immediately adjacent grid elements, and in which a suitable cement is employed, covering the two surfaces of the insulating spacer plate, which is baked following assembly of the resistor elements. Such a construction, after baking, makes a more rigid resistor assembly which is not as susceptible to movement under the influence of high magnetic forces as would be the case if cement were not used.

Further objects and advantages will readily

2

become apparent upon reading the following specification taken in conjunction with the drawings, in which:

Figure 1 is a somewhat diagrammatic side elevational view, partly in vertical section, of a circuit interrupter, particularly one of the high voltage type, utilizing our improved resistor assembly, the contact structure being shown in the closed-circuit position;

Fig. 2 is an enlarged top plan view of our improved resistor assembly;

Fig. 3 is a vertical sectional view taken along the line III—III of Fig. 2;

Fig. 4 is a side vertical sectional view through our improved resistor assembly taken on the line IV—IV of Fig. 2;

Fig. 5 is a plan view of one of the cast grid resistor elements;

Fig. 6 is an end elevational view of the resistor element shown in Fig. 5;

Fig. 7 is a plan view of one of the insulating plates used in the construction of our improved resistor assembly;

Fig. 8 is a top plan view of one of the conducting spring washers;

Fig. 9 is a vertical sectional view taken through the spring washer of Fig. 8 along the line IX—IX thereof;

Fig. 10 is a plan view of one of the insulating washers used in the assembly of our improved resistor arrangement;

Fig. 11 is a vertical sectional view taken along the line XI—XI through the insulating washer of Fig. 10; and

Fig. 12 illustrates a modified construction similar to the construction set forth in Figs. 1—11, inclusive, but shows in fragmentary fashion the use of a suitable cement providing improved adherence between the resistor elements and the insulating spacing plate.

It will be apparent to those skilled in the art that certain features of our improved resistor assembly may be utilized in other types of constructions and installations other than those pertaining to circuit interrupters. However, certain problems become more apparent, and must be given special attention, when the use of a resistor assembly is employed in connection with a circuit interrupter, particularly a circuit interrupter of the high voltage type in which vibration may be a considerable problem during the opening and closing operations and in which high amperage currents may be involved.

On compressed air circuit breakers of the orifice type, as well as the cross-blast type, it is well

known that the interrupting capacity of the breakers can be increased considerably by the use of shunting resistors. There are several methods available and well known to the art for inserting the resistor and interrupting the residual current. On a cross-blast type breaker, the resistance may be inserted by means of an auxiliary terminal in the arc chute which arcs over to the moving contact when gases develop during interruption. The residual current is then interrupted by the continued movement of the movable contact while still in the area of the air blast. On a new 69 kv. orifice type breaker, presently to be described, which has two series-connected contacts, the resistor is connected permanently across one contact, and the residual current is interrupted by the delayed opening of the second contact.

Referring to the drawings, and more particularly to Fig. 1 thereof, we have disclosed one typical example of a circuit interrupter which utilizes a resistor assembly to shunt a pair of contacts, and in which a serially connected pair of contacts are utilized to interrupt the residual current that will then pass through the resistor. The interrupter shown is of the compressed gas type adapted for high voltage application, such as 69 kv., but certain features of our invention are obviously usable in connection with other types of circuit interrupters, such as those adapted only for low voltage application.

The reference character 1 designates a tank or reservoir mounted on supports 2, the latter resting upon a suitable foundation. Extending upwardly in a vertical direction from the tank 1 is a blast tube 3, of insulating material, which supports an interrupter assembly, generally designated by the reference character 4. The interrupter assembly 4 comprises a pair of serially connected stationary contacts 5, 6 and a pair of serially connected cooperable movable contacts 7, 8. The movable contacts 7, 8 are biased toward the closed position, as shown in Fig. 1, by means of a pair of compression springs 7B, 8B.

The movable contacts 7, 8 are supported in a movable contact assembly, generally designated by the reference character 9, and essentially including a pair of concentric cylinders 9a and 9b. The separation between the cylinders 9a and 9b provides a substantially annular gas conducting space 9c which permits the ready flow of compressed gas upwardly through the blast tube 3 and to the movable contacts 7, 8 so that the latter may quickly be opened by the gas pressure, but in a desired sequence. Obviously, the movable contacts 7, 8 are separated away from the stationary contacts 5, 6 against the opposition exerted by the compression springs 7B, 8B during the existence of high pressure conditions.

When the gas pressure is lowered due to closing of the blast valve 10 and leakage of air occurs out of the interrupter assembly 4 through the expansion chambers 11, 12 by virtue of the exhaust openings 13 provided therein, the compression springs 7B, 8B will serve to again close the contact structure. However, this reclosure of the contact structure occurs after the opening of the serially connected isolating switch 14, as will be presently explained.

Shunting the lower set of contacts 5, 7 is a resistor assembly 15, including the resistance R, which carries the current between the contacts 5 and 7 after the latter have opened and the arc therebetween has been extinguished by the upwardly flowing gas blast. The upper set of

contacts 6, 8 is purposely delayed in its opening operation, so that at the time it is opened the lower arc between the contacts 5 and 7 will have already been extinguished, and at this time the current passing through the interrupter will be traversing the resistor R.

As is well known by those skilled in the art of circuit interruption, the use of a shunting resistor R across the lower set of contacts 5, 7 reduces the amperage value of the current to be interrupted, and also improves the power factor, thereby making the upper arc easier to interrupt.

As shown in Fig. 1, the movable contact assembly 9 is supported by an insulating tube 16, the latter resting upon the expansion chamber 12, previously referred to. There is provided an orifice 17 in the lower stationary contact 5 which permits the gas blast to pass therethrough during the opening operation. This gas blast, after passing through the orifice 17, and extinguishing the arc between the contacts 5, 7, passes into the expansion chamber 12 by one or more conduits 18 to collect within the expansion chamber 12, and to raise the pressure therein. The purpose of raising the pressure within the expansion chamber 12 is to increase the dielectric strength of the gas adjacent the separated contacts 5, 7 and also to cut down the amount of gas flow.

In like manner, there is provided the expansion chamber 11 at the upper end of the interrupter assembly 4, which rests upon a second insulating tube 19, the tube 19 in turn resting upon the movable contact assembly 9. Preferably, a line terminal 20 is associated with the upper expansion chamber 11.

The compressed gas circuit interrupter, shown in Fig. 1, has an operating mechanism 21 enclosed within a housing 22 which serves to actuate an insulating operating rod 23 at a proper time to effect upward swinging, or counterclockwise rotation, of the isolating switch blade 14 away from the stationary disconnect contact fingers 24 associated with the terminal member 25 disposed at the upper end of an insulating tube 26, the latter being supported upon the tank 1. Also associated with the terminal member 25 is a second line terminal 27, to which the external circuit may be connected.

In the closed circuit position of the interrupter, as shown in Fig. 1, the electrical circuit passing therethrough includes line terminal 20, conducting expansion chamber 11, stationary contact 6, movable contact 8, inner cylinder 9b of the movable contact assembly 9, lower movable contact 7, stationary contact 5, through the conducting lower expansion chamber 12, and through the conducting isolating switch blade 14 to the stationary disconnect fingers 24, and hence to the other line terminal 27 of the interrupter.

The blast valve 10, previously referred to, is of the differential-pressure type, being normally closed by an equalization of the gas pressure upon its two sides. A light spring 28 is provided to bias the blast valve 10 toward its closed position, but the spring 28 is insufficient by itself to close the blast valve 10 in opposition to the pressure existing within the tank 1, which pressure may approach the value of 250 pounds per square inch. A valve controlling pipe 29 is provided to equalize the gas pressure on the two sides of the differential blast valve 10, and to effect the opening of the blast valve 10 by reducing the pressure therebeneath. The high pressure gas below the

blast valve 10 may be exhausted out through the valve controlling pipe 29 by suitable pneumatic valves, as well known by those skilled in the art.

Briefly, an opening operation of the interrupter disclosed in Fig. 1, includes an exhausting of the gas below the differential blast valve 10 by the use of suitable pneumatic control equipment permitting such exhausting to take place through the valve controlling pipe 29. The dumping of such high pressure gas below the blast valve 10 permits the high pressure gas within the tank 1 to force the blast valve 10 downwardly in opposition to the light spring 28, and thereby permitting the upward flow of compressed gas through the blast tube 3. This upward flow of compressed gas first opens the lower set of contacts 5, 7, suitable delaying means being provided (by suitable constricting action upon the gas flow) so as to prevent immediate opening of the upper set of contacts 6, 8.

The initial opening of the lower set of contacts 5, 7 draws an arc which is extinguished by the gas flow passing between the contacts 5, 7 and exhausting through the orifice 17 associated with the stationary contact 5. This gas flow collects within the expansion chamber 12, despite the slight leakage through the exhaust opening 13, and the dielectric strength of the gas adjacent the contact structure 5, 7 is improved, and the flow of gas therebetween and out through the orifice 17 is diminished by the rising gas pressure within the interior of the hollow stationary contact 5 and within the lower expansion chamber 12. The shunting resistor R, shunting only the contacts 5, 7, affords a parallel path for the current flow, but the amperage of the current flow is reduced by its passage through the resistor R.

Subsequently, the upper set of contacts 6, 8 are opened, and the gas passes therebetween and out through an orifice 30 associated with the upper hollow stationary contact 6. This exhaust gas collects within the upper expansion chamber 11 despite the bleeder opening 13, with the result that the gas pressure within the upper expansion chamber 11 rises, to improve the dielectric strength of the gas adjacent the upper contact structure 6, 8, and also diminishes the quantity of gas passing out through the orifice 30 by virtue of the rising pressure within the expansion chamber 11 and within the interior of the hollow stationary contact 6.

The extinction of the upper arc between the contacts 6, 8 by the gas flow, as previously described, breaks the residual current passing through the interrupter. The circuit is then interrupted. Subsequently, the delayed action of the operating mechanism 21 caused pneumatically by a delayed passage of gas flow through the conduit 31 into the mechanism 21 effects upward counterclockwise swinging rotative motion of the isolating switch blade 14 away from the stationary disconnect contacts 24, to provide thereby an isolating gap in the previously opened circuit.

Such an isolating gap permits the contact structure to be reclosed since the voltage will then be held by the isolating gap. In other words, following opening of the isolating switch 14, suitable means, not shown, effects high pressure gas flow upwardly through the valve controlling pipe 29 so that the pressure will be equalized on both the top and bottom sides of the differential blast valve 10. Since this pressure is equalized, the force exerted by the light compression spring 28 is sufficient to close the

blast valve 10, and thereby halt the upward flow of compressed gas through the blast tube 3. The high pressure gas within the expansion chambers 11, 12 leaks out through the openings 13 so that the pressure adjacent the movable contact assembly 9 decreases, thereby permitting the compression springs 7B, 8B to effect reclosure of the contact structure, this all occurring following opening of the disconnect switch 14.

10 Certain features of the circuit interrupter disclosed in Fig. 1 including a more elaborate description of the purpose of the shunting resistor R are described and claimed in United States patent application Serial No. 74,406, filed February 3, 1949, now United States Patent 2,627,-005, issued January 27, 1953, to Benjamin P. Baker, Erling Frisch, Wayne S. Aspey and John B. MacNeill, and assigned to the assignee of the instant application. Other features relating to 15 the interrupter assembly are described and claimed in United States patent application Serial No. 74,407, filed February 3, 1949, now United States Patent 2,602,868, issued July 8, 1952, to Benjamin P. Baker, Erling Frisch and Howard 20 M. Wilcox, and also assigned to the assignee of the instant application. The pneumatic control for the aforementioned compressed gas circuit interrupter, which is of the 69 kilovolt type, is described and claimed in the United States patent 25 application, Serial No. 73,516, filed January 29, 1949, by Benjamin P. Baker and Howard M. Wilcox and likewise assigned to the assignee of 30 the instant application.

We have found that for maximum efficiency 35 the ohmic value of the resistor R must be quite low. On the particular 69 kilovolt breaker, heretofore described, the ohmic value was 12 ohms to obtain the desired interrupting capacity. With this resistor, the residual current reaches 40 a maximum value of 3,700 amperes based on 44 kilovolts phase-to-ground voltage.

The design of a resistor for this type of service presents several problems not ordinarily encountered in the design of resistors for other purposes. In the first place, the resistor must be 45 adequately insulated for the high voltage, while occupying minimum space. Moreover, the resistor elements must be securely braced to prevent shifting and possible flashovers between the 50 resistor elements as a result of the large magnetic forces developed by the high currents during interruption. While the resistor must carry heavy short-circuit currents, it is required to carry current for only the very short time required to open the circuit interrupter and extinguish the arc. In addition, it is desirable to make 55 the resistor such that it will be easy to assemble in the shop by unskilled workmen, and moreover being assembled without the use of welding or soldering.

60 Referring to Figs. 5 and 6, there is shown one of the grid resistor elements 32, which is preferably cast out of a suitable metal, which will not only have a high specific resistance but will be able to withstand the shock and concussion caused by the opening and closing of the interrupter of Fig. 1. It will be observed that the zigzag turns 33 of the resistor element 32 are 65 extended laterally to such an extent that they come approximately along the same outer lines 33' as is defined by the lug portions 34. It will also be observed that the lug portions 34 have relatively large apertures or openings 35 provided therethrough, the purpose for which will 70 appear more clearly hereinafter. Further, it will 75

be observed that the lug portions 34 take space 34' which is provided by shorter turns 33 so that the result is a substantially rectangularly-shaped resistor element, as clearly shown in Fig. 5, providing the maximum resistance area with the minimum surface area.

Referring to Fig. 6, which shows an end elevational view of the resistor element 32, it will be observed that the lug portions 34 do not rise, or are not elevated or depressed, above or below the planes of the turns 33, or in other words, no elevated or depressed bosses are formed by the lug portions 34. This has the advantage that in assembling the resistor elements 32 a maximum number of such elements 32 may be stacked with a minimum longitudinal space along the stack. If the lug portions 34 were raised, or formed bosses, with respect to the plane of the turns 33, there would clearly be a fewer number of such grids 32 assembled for the same amount of longitudinal space, as compared to the former case in which the lug portions 34 are exactly on a level with the turns 33 of the element 34. Further advantages will be set forth later.

Referring to Fig. 7, there is shown a plan view of one of the insulating plates provided between each of the resistor elements 32. This plate or plate portion is designated by the reference numeral 36, and is preferably made of a highly insulating material which is not susceptible to breakage or to thermal deterioration. We have found mica to be such a suitable material. It will be noted that there is provided in the mica plate 36 an aperture or opening 37 and a cut-out portion 38 at the diagonal corners of the plate 36, the purpose for which will be more clearly explained hereinafter.

Referring to Figs. 8 and 9, attention is directed to the conducting spring washers 39, which are used in our improved resistor assembly 15 to provide good contacting engagement between the lug portions 34 of immediately adjacent resistor elements 32 at the places where conduction between such resistor elements 32 is desired. It will be observed, with reference to Figs. 8 and 9, that the metallic washer 39 is of concave shape, as indicated at 40, and preferably the thickness D of the washer 39 is less than the thickness of the insulating plate 36, the purpose for which will be subsequently explained. However, it will be observed that the concave shape 40 of the spring washer 39 is such that the thickness S as indicated in Fig. 9, is greater than the thickness of the mica plate 36.

Referring to Figs. 2, 3 and 4, it will be apparent that the resistor assembly 15 utilizes a pair of end castings 42, 43. The upper casting 42 has a laterally extending bracket portion 44 with a plurality of apertures 45 (Fig. 4) extending therethrough, so that in the assembled position of the resistor assembly 15, as viewed in Fig. 1, suitable bolts may be utilized, passing through the apertures 45 of the bracket 44 to secure the upper end of the resistor assembly 15 to the outer cylinder 20 of the movable contact assembly 9, as at 46. Thus, there is provided good physical securing, and also good electrical engagement between the upper end of the resistor assembly 15 and the movable contact assembly 9.

The lower casting 43 has a pair of threaded holes 48 provided therein so that suitable bolts may secure the lower casting 43 to the lower conducting metallic expansion chamber 12 of 75

Fig. 1, as at 50. The result is good physical attachment of the lower end of the resistor assembly 15 to the expansion chamber 12, and also good electrical contact being provided therebetween.

The lower casting 43 also has a pair of apertured lug portions 47 which are internally threaded to receive a pair of metallic studs 48, the latter being suitably secured to the lower ends of a pair of insulating guide rods 49. In the assembling operations, the first step is to threadedly secure the guide rods 49 into the lower casting 43. The grid elements 32 are then placed upon the guide rods 49 so that the guide rods 49 pass through the apertures 35 of the lugs 34 of the resistor elements 32. Between adjacent resistor elements 32 are disposed the mica plates 36, alternately placed so that the cutout portion 38 of the mica plate 36 occurs at the place where the lugs 34 of the elements 32 are to be electrically connected. The aperture 37 of the mica plate 36 is just large enough to receive the guide rod 49 at the unconnected end of the grids 32.

Between the lug portions 34, which are to be electrically connected, adjacent the cutout portion 38 of the plate 36, a Phosphor bronze spring washer 39, previously described in connection with Figs. 8 and 9, is utilized. Also, wherever the spring washer 39 is utilized, an insulating washer 51 is employed within the spring washer, the purpose for which will appear more fully hereinafter.

Fig. 3 shows more clearly the assembling steps taken to insure good insulating connections and good electrical connections. As shown in Fig. 3, the mica plates 36 extend beyond the edges of the grids 32 and thus provide a long creepage path having a breakdown voltage considerably in excess of the requirements for the voltage rating. The mica plates 36 have sufficient thickness to insulate substantially the whole surface area of each element 32 from its neighbor.

As shown, the resistor stack 15 is supported between the two castings 42 and 43, which are secured together by two insulating straps 52. Bolts 53 and nuts 54 rigidly secure the castings 42, 43, to the spacing straps 52, as shown more clearly in Fig. 3. In order to prevent shifting of the grids or resistor elements 32, they are compressed evenly over their entire surface area by means of eight heavy springs 55 which, in the particular instance concerned with, produce a total pressure in the neighborhood of 1,000 to 2,000 pounds. The springs 55 are loaded by means of two set screws 56, which threadedly pass through the upper casting 42 and bear upon an upper steel spring plate 57. The lower ends of the compression springs 55 bear upon a brass spring plate 58 having notches 58' for ventilation. The brass spring plate 58 preferably has a plurality of screws 59 passing therethrough, as shown in Fig. 3, with a plurality of washers 60 surrounding the upper shank portion of the screw 59, with a nut 61 threaded thereupon. The purpose of the screws, washers and nuts 59, 60 and 61 is to provide a lower spring seat for the compression spring 55, so that there will not take place any lateral movement of the spring 55 to change its position due to vibration of the interrupter.

To insure good contacting engagement between the lower spring plate 58 and the upper spring plate 57, we provide a pair of conducting straps 63 having a pair of apertures at their outer ends. One of the apertures receives the screw 59 and is

pressed against the lower spring plate 58 by the lower end of one of the compression springs 55, as shown more clearly in Fig. 3. The other aperture in the conducting strap 63 receives the upper end of the guide rod 49 and is pressed against the upper spring plate 57 by a metallic spacing tube 64, as shown more clearly in Fig. 4. The two conducting straps 63 are disposed at opposite ends of the resistor assembly 15, as more clearly shown in Fig. 2.

The electrical circuit passing through the resistor R of the assembly 15 hence comprises the top casting 42, the set screws 53, the upper spring plate 57, conducting straps 63, lower spring plate 58, Phosphor bronze washer 39 (left-hand side of Fig. 3), left lug 34 of the top resistor element 32 (Fig. 3), thence through the turns 33 of the top resistor grid 32 to the right-hand lug 34 of Fig. 3. The circuit then extends through another spring washer 39 to the lug portion 34 of the second resistor element 32 and so on in a zigzag path down to the right lug 34 of the lowermost resistor element 32 of Fig. 4. Since there is provided a mica plate 36 below the lowermost resistor element 32, as shown in Fig. 4, again resort is had to a spring washer 39 (right-hand side of Fig. 4) to conduct the current from the lug portion 34 of the lowermost resistor element 32 to the lower conducting casting 43. The circuit then extends through the bolts, not shown, which secure the lower casting 43 to the expansion chamber 12 (Fig. 1), and thence to the lower stationary contact 5.

The lower casting 43 is also provided with a laterally extending bracket portion 65 which is drilled and tapped to receive bolts 66 which secure an insulating rectangularly-shaped housing 67 to the resistor assembly 15. However, there is provided space, such as at 68, between the lower casting 43 and the inner surface of the housing 67 so as to permit free circulation of air upwardly through the interior of the housing 67 and thereby pass the several grids 32 and notches 58' of spring plate 58.

The lower spring plate 58 is preferably made of a relatively thin material with sufficient flexibility, such as brass, to distribute the spring pressure evenly upon the grids 32. As mentioned, the grids 32 are made of a special alloy which has a very high specific resistance and is sufficiently ductile to be shockproof. Preferably, also the grids 32 are made free of projections which might puncture the mica insulating plates 36 and thereby prevent even distribution of pressure from grid to grid.

The assembling operations will now be described. The grids and the mica insulating plates 36 are assembled upon the bottom casting 43 with the insulating tie rods 49 projecting upwardly from the lower casting 43 and fitting into the guide holes 35 provided in the grids 32. The tie rods 49 likewise serve to locate the mica plates 36. The grids are electrically connected in series by placing the Phosphor bronze washers 39 between alternate terminals of adjacent grids. The large hole or cutout 38 in the plate 36 at this point permits insertion of the washers 39. The spring washers 39 are made of a slightly thinner material than the mica plates 36 to obtain good contact pressure, and at the same time to prevent the washers 39 from going solid and thereby preventing distribution of pressure on the rest of the grid surface, which would be the case if the spring washers 39 were thicker when pressed flatter than the mica plates 36. The

insulating spacers 51, placed inside the washers 39 and the holes 35 in the resistor grids 32, serve to give sufficient insulation creepage path between non-connected grids 32 around the tie rods 49.

The complete assembly, including the springs and the upper and lower spring plates 57, 58 are held together temporarily by tightening the tie rod nuts 69 (Fig. 3) to obtain a slight tension in the tie rods 49. The nuts 69 thread upon short stud lengths 49' secured to the upper end of the tie rods 49. After the insulating straps 52 and upper casting 42 have been assembled, the springs 55 are compressed to final loading by means of the set screws 56. Correct loading is obtained by compressing the springs 55 to a length determined by the metallic spacer tubes 64, as shown more clearly in Fig. 3. As shown, the spacer tubes 64 are disposed around the tie rods 49 between the two spring loading plates 57, 58.

The rectangular insulating shield or housing 67 covers the resistor assembly 15 and protects it from damage. The air spacing between the grids 32 and the cover 67 permits free circulation of cooling air about the grids 32.

From the foregoing description of our improved resistor assembly, it will be apparent that we have provided a novel means of stacking flat cast grids 32 and mica plates 36 under pressure to obtain adequate insulation with a minimum space factor and to permit bracing of the grids 32. The use of the spring washers 39 provides good contact between adjacent grids 32, and the two insulating guide rods 49 provide a simple guide means for locating the grids 32 and the mica plates 36 during the stacking operation and to hold the grid assembly 15 together until final pressure is applied by tightening the set screws 56. The tie rods 49 also prevent shifting of the grids 32 and of the plates 36 on the completed resistor assembly.

It will moreover be apparent that we have provided bracing of the grids 32 by applying a high even pressure over the entire surface by means of a number of compression springs 55.

Fig. 12 shows a modification of our invention in which a suitable cement 73 is employed covering the two surfaces of the insulating mica plate 36 to provide improved adherence between the resistor elements 32 and the mica plate 36. In order to prevent motion of the zigzag grids 32 under the influence of the magnetic forces, it was found desirable to provide greater adhesion between the grids 32 and the mica spacer 36 than could be provided by pressure alone. In order to do this, we painted the top and bottom surfaces of the mica plate 36 with a cement, such as a urea-formaldehyde cement, and following assembly of the resistor elements 32 baked the entire assembly 15 for several hours. This cement 73, as shown in Fig. 12, stuck the grids 32 to the mica plate 36, and the excess cement was squeezed out forming a spacer 74 between the zigzag turns 33. The entire structure was, therefore, much more solid and stronger to resist magnetic forces and mechanical shock.

Although we have described our invention as particularly applied to a high voltage compressed air circuit interrupter, it will be apparent to those skilled in the art that certain features of our invention are applicable wherever resistor assemblies may be utilized. Merely for the purposes of illustration have we disclosed our improved resistor as applied to a high voltage compressed gas circuit interrupter.

Although we have shown and described a specific structure, it is to be clearly understood that the same was merely for the purpose of illustration, and that changes and modifications may readily be made therein by those skilled in the art without departing from the spirit and scope of the appended claims.

We claim as our invention:

1. A resistor assembly including a plurality of flat plate-like resistor elements, each such resistor element having a plurality of turns, each resistor element having one or more apertured lug portions, the two sides of each lug portion of each resistor element being in the same planes as the two sides of the turns, one or more insulated tie rods passing through the apertured lug portions, an insulating spacer plate disposed between immediately adjacent resistor elements so as to cover a substantial portion of the area of the resistor elements, resilient means for applying a resilient pressure over the resistor elements in their assembled state, a resilient spring washer between contacting lug portions for lowering the contact resistance therebetween, each such spring washer having an expanded thickness greater than that of the insulating plate, and a contracted thickness less than that of the insulating plate.

2. A resistor assembly including a plurality of flat plate-like resistor elements, each such resistor element having a plurality of turns, each resistor element having one or more apertured lug portions, the two sides of each lug portion of each resistor element being in the same planes as the two sides of the turns, one or more insulated tie rods passing through the apertured lug portions, an insulating spacer plate disposed between immediately adjacent resistor elements so as to cover a substantial portion of the area of the resistor elements, resilient means for applying a resilient pressure over the resistor elements in their assembled state, a resilient spring washer between contacting lug portions for lowering the contact resistance therebetween, each such spring washer having an expanded thickness greater than that of the insulating plate, a contracted thickness less than that of the insulating plate, and an insulating washer disposed inside of each spring washer, considering a section between the ends of the resistor assembly, encircling the tie rod and disposed within the apertures of adjacent contacting lug portions to give sufficient creepage between non-connected resistor elements around the tie rod.

3. A circuit interrupter including a resistor assembly including a plurality of flat plate-like resistor elements, each such resistor element having a plurality of turns, each resistor element having one or more apertured lug portions, the two sides of each lug portion of each resistor element being in the same planes as the two sides of the turns, one or more insulated tie rods passing through the apertured lug portions, an insulating spacer plate disposed between immediately adjacent resistor elements so as to cover a substantial portion of the area of the resistor elements, resilient means for applying a pressure over the resistor elements in their assembled state, a resilient spring washer between contacting lug portions for lowering the contact resistance therebetween, each such spring washer having an expanded thickness greater than that of the insulating plate, and a contracted thickness less than that of the insulating plate.

4. A circuit interrupter including a resistor as-

sembly including a plurality of flat plate-like resistor elements, each such resistor element having a plurality of turns, each resistor element having one or more apertured lug portions, the two sides of each lug portion of each resistor element being in the same planes as the two sides of the turns, one or more insulated tie rods passing through the apertured lug portions, an insulating spacer plate disposed between immediately adjacent resistor elements so as to cover a substantial portion of the area of the resistor elements, resilient means for applying a pressure over the resistor elements in their assembled state, a resilient spring washer between contacting lug portions for lowering the contact resistance therebetween, each such spring washer having an expanded thickness greater than that of the insulating plate, a contracted thickness less than that of the insulating plate, and an insulating washer disposed inside of each spring washer, considering a section between the ends of the resistor assembly, encircling the tie rod and disposed within the apertures of adjacent contacting lug portions to give sufficient insulating creepage between non-connected resistor elements around the tie rod.

5. A resistor assembly including a plurality of flat plate-like resistor elements, each such resistor element having a plurality of turns, an insulating spacer plate disposed between immediately adjacent resistor elements so as to cover a substantial portion of the area of the resistor elements, and a cement coating on at least one side of the insulating spacer plate, to provide greater adherence between the insulating spacer plate and one of the resistor elements immediately adjacent to the coated surface of the insulating spacer plate.

6. A resistor assembly including a plurality of flat plate-like resistor elements, each such resistor element having a plurality of turns, an insulating spacer plate disposed between immediately adjacent resistor elements so as to cover a substantial portion of the area of the resistor elements, and a cement coating on at least one side of the insulating spacer plate, to provide greater adherence between the insulating spacer plate and one of the resistor elements immediately adjacent to the coated surface of the insulating spacer plate, and means for applying a pressure over the resistor elements in their assembled form.

7. A resistor assembly including a plurality of flat, plate-like resistor elements, each such resistor element having a plurality of turns, each resistor element having one or more lug portions with openings therethrough, one or more insulated tie rods passing through the lug portions, an insulating plate portion between adjacent resistor elements, and a resilient spring washer between contacting lug portions for lowering the contact resistance therebetween, each such spring washer having an expanded thickness greater than that of the insulating plate portion, and a contracted thickness less than that of the insulating plate portion.

8. A resistor assembly including resistor elements having flat lug portions with openings therethrough, at least one of said lug portions being connected to the next adjacent lug portion on one side and unconnected from the adjacent lug portion on the other side, a tie rod with an external insulating surface passing through the openings in the flat lug portions of the resistor elements, one or more insulating washers, certain of the openings in the connected lug portions being larger than the tie rod to accommodate one of said insulating washers therein, an insulating

plate portion with an opening therethrough of only slightly larger dimension than the tie rod but smaller than said larger openings, a resistor element on the other side of the insulating plate portion having a lug portion unconnected with the lug portion of the next adjacent resistor element, and said insulating washer maintaining the edges of said larger openings in the flat connected lug portions away from the smaller opening in the insulating plate portion to give sufficient insulation creepage between the connected and non-connected lug portions of the resistor elements.

9. A resistor assembly including a plurality of flat plate-like resistor elements, each such resistor element having a plurality of turns, an insulating spacer plate disposed between immediately adjacent resistor elements so as to cover a substantial portion of the area of the resistor elements, and a cement coating on both sides of the insulating spacer plate, to provide greater adherence between the insulating spacer plate and both of the

5

resistor elements immediately adjacent to the coated surfaces of the insulating spacer plate.
